(57) **CLAIM**

The ornamental design for a pelvic floor muscle strength measure device, as shown and described.

DESCRIPTION

1. Pelvic floor muscle strength measure device

1.1 : Perspective

1.2 : Front

1.3 : Back

1.4 : Left

1.5 : Right

1.6 : Top

1.7 : Bottom

The broken lines shown in the drawings illustrate portions of the pelvic floor muscle strength measure device that form no part of the claimed design.
